DESIGN.

A. WEBSTER, Jr.
Carpets.

No. 6,339.

Patented Jan. 7, 1873.

UNITED STATES PATENT OFFICE.

ANDREW WEBSTER, JR., OF NEW YORK, N. Y., ASSIGNOR TO CHARLES M. BAILEY, OF SAME PLACE.

DESIGN FOR CARPETS.

Specification forming part of Design No. 6,339, dated January 7, 1873.

To all whom it may concern:

Be it known that I, ANDREW WEBSTER, Jr., of the city, county, and State of New York, have invented a new and original Design for a Carpet, of which the following is a specification:

The accompanying photograph fully illustrates my new design.

This invention relates to a new carpet design which contains three different styles of squares arranged side by side to form regular parallel rows at right angles to each other. Every other square in these rows is made with a mottled background and star-shaped center

therein, as shown; of the remaining squares those in one row have small square center-pieces within a cross-shaped figure, which is ornamented by leaves, &c., as shown; while those in the next row contain similar-shaped figures similarly ornamented, but with lozenge-shaped center-pieces, as shown.

I claim as my invention—

The design for a carpet containing the three styles of ornamented squares, as shown.

ANDREW WEBSTER, JR.
